UNITED STATES PATENT OFFICE.

NEWTON H. BOLTON, OF OMRO, WISCONSIN.

IMPROVEMENT IN MACHINES FOR SHARPENING SAWS.

Specification forming part of Letters Patent No. 120,700, dated November 7, 1871.

To all whom it may concern:

Be it known that I, NEWTON H. BOLTON, of Omro, in the county of Winnebago and State of Wisconsin, have invented a new and useful Improvement in Saw-Sharpener Machines; and I do hereby declare the following to be a full, clear, and exact description thereof, which will enable others skilled in the art to which my invention appertains to make and use the same, reference being had to the accompanying drawing forming part of this specification, in which—

Figure 1 is an end view of my improved machine, and Fig. 2 is a top view of the same.

Similar letters of reference indicate corresponding parts in both figures of the drawing.

My invention relates to a mechanism for sharpening circular or other mill-saws; and to that end consists in a metal frame, within which is secured a shaft carrying an emery-wheel so arranged within a hollow mandrel as to admit of a longitudinal movement simultaneously with a rotating movement of the same, whereby the wheel is adjusted to the teeth, the frame carrying the shaft and mandrel being pivoted to the main frame in a manner which admits of a tilting movement, by which the wheel is adjusted to the desired pitch or angle of the tooth of the saw.

In the drawing, A is the frame, which may be as shown, or may be made in any manner that will receive the moving parts of the machine. Firmly affixed to the front extremity of said frame are vertical uprights *a a*, which extend upward slightly above the upper surface of the same. To and between the said uprights is pivoted a horizontal metal frame, B, the form of which is shown in Fig. 2, and which is so arranged as to admit of a tilting movement. Within and to the upper surface of the curved portion of said metal frame is secured a hollow mandrel, C, which is so arranged as to admit of a free and easy rotating movement. Upon said mandrel is secured a pulley, D, the center of which, laterally with the mandrel, is in line with the center of the pivots, securing the said frame to the uprights. Upon and around the said pulley is a belt, *d*, which extends backward to and around wheel *D'* on the main driving-shaft *E*, which shaft is secured within boxes *e e* affixed to the rear and upper surface of the frame. Mounted upon the outer end of said shaft *E* is a pulley, F, around which passes a belt (not shown)

communicating with suitable machinery, from which the requisite power for rotating the mandrel is obtained. Loosely affixed within the said mandrel C is a shaft, C', one end of which is supported within the box *b*, secured to the end of the frame B, the whole being so arranged as to allow the said shaft a free and easy longitudinal movement. Within that portion of the said shaft, passing through the mandrel I provide a longitudinal groove or seat, which receives a set-screw, *g*, secured to and within the mandrel, by which a rotary motion is imparted to the shaft uniform with the rotation of the mandrel. Loosely secured to and upon the side of frame B, toward the main frame, is a metal slide, G, which is so arranged as to admit of a free and easy movement. Firmly attached to, or formed as a part of said slide, is a rack, H, which engages a gear-wheel, H', affixed to and upon the shaft I secured to and passing laterally through frame B, and is provided at its outer end with a crank-wheel, *h*, for rotating the same, by which means a reciprocal rectilinear movement may be imparted to the slide by the reciprocal rotary movement of wheel *H'*. Within said slide, near its center, is a vertical groove, *i*, which receives a collar, J, rigidly secured upon shaft C', by which means a longitudinal movement is imparted to the shaft by the movement of the slide. Mounted upon the outer end of shaft C' is an emery-wheel, K, the periphery of which is bevelled to an angle near forty-five degrees to its sides, as shown in the drawing.

In using my said improved machine, the frame is arranged in a position which brings the emery-wheel at a right angle with the saw and in close proximity to the teeth. A rotary motion is then imparted to the wheel by the rotation of shaft C', which motion is communicated thereto from the main driving-wheel *D'* of shaft *E*, through the medium of belt *d*, pulley *D*, and mandrel *C*, whereby the teeth of the saw are ground to the desired edge and pitch by the contact of the wheel therewith; the tilting movement of the frame carrying the shaft, together with the longitudinal movement of the shaft, being such as to admit of adjusting the wheel to the desired point, thus enabling the operator to grind several teeth without a movement of the saw. It will be noticed that the center of the pulley upon the mandrel is in a line laterally with the pivots

or fulcrum of the frame, the object of which is to allow the center of the said pulley to retain the same relative position with the driving-wheel as the frame is tilted to the requisite angle, by which means the belt is retained in proper position on the pulley.

Having thus described my invention, what I claim as new, and desire to secure by Letters Patent, is—

The combination of frame B, mandrel C, shaft

C', slide G, rack, H, and wheel H', as described, whereby a longitudinal movement may be imparted to the said shaft C' simultaneously with a tilting movement of the same, the whole arranged to operate the emery-wheel K, substantially as and for the purpose specified.

NEWTON H. BOLTON.
